UNITED STATES PATENT OFFICE.

EARL F. COPP, OF MONTCLAIR, NEW JERSEY.

TONE-MODIFIER.

1,354,171.

Specification of Letters Patent. Patented Sept. 28, 1920.

Application filed April 29, 1920. Serial No. 377,429.

To all whom it may concern:

Be it known that I, EARL F. COPP, a citizen of the United States, and a resident of Montclair, Essex county, and State of New Jersey, have invented certain new and useful Improvements in Tone-Modifiers, of which the following is a specification.

The present invention relates to the modifying of the tone or sound produced by a phonograph.

The objects of the invention primarily are to provide practical and efficient means for controlling the volume and tonal quality of the sound and also to provide such a device in the form of an attachment which may be readily applied to an ordinary sound box.

Briefly, the invention involves the combination of a tone modifying element and supporting means therefor and by which the same may be adjusted toward and away from the diaphragm of the sound box.

The invention involves various other novel features of construction, combinations and arrangements of parts, as will be disclosed in the following specification.

In the accompanying drawing I have illustrated the invention embodied in several of the different possible forms thereof, but wish it understood that the same may be further modified and changed without departure from the true spirit and scope of the invention as herein defined and claimed.

In the drawing referred to:

Figure 1 is a perspective view, and Fig. 2 is a sectional view of one of the simplest forms of the invention.

Fig. 3 is another sectional view, illustrating a modification in the form of the adjusting device.

Figs. 4 and 5 are face and sectional views respectively of another form of tone modifying element.

Figs. 6 and 7 are face and sectional views respectively, illustrative of another form of tone modifying means and the adjustment thereof.

In the present illustrations, I have shown in each instance the invention as made in the form of an attachment engageable over an ordinary sound box and have illustrated the sound box as of the usual conventional type, involving a box body 10, containing a diaphragm 11 to which there is connected the usual stylus lever 12.

According to my invention, the tone is

controlled by a "damping" action on the diaphragm and by reducing the area which is free to vibrate.

In the form of the invention first disclosed (Figs. 1 and 2), the controlling element consists of a pad 15 of resilient or semi-resilient material, such as felt, rubber or the like, carried by a plate or plates 16 and which is adjusted with respect to the diaphragm by means of a screw 17.

This adjusting screw is shown as mounted in a support 18 in the form of a spider having spring supporting arms 19 "clipped" over the rim of the sound box and is shown as connected with the backing plates 16 of the pad by means of a bracket 20 "arched" over the stylus lever. This screw is furthermore shown as shouldered at its inner end at 21 and as connected by means of this shouldered portion with the head of the arched bracket and therefore capable of shifting the tone modifying pad in both directions.

To prevent rotation of the pad, I have shown a pin 22 projecting inwardly from the screw support 18 through the head of the arched bracket, said bracket sliding thereover as the screw is turned in one direction or the other.

In order that the pad shall not interfere with the free action of the stylus lever, I have shown the same as having a slot 23 extending inward from the edge thereof, past the point where the stylus lever is attached to the diaphragm, this making the pad generally of horse shoe shape.

The device in the form illustrated is applied to a sound box by simply snapping the spring arms over the rim of the sound box. If the sound produced is too loud or strident, or otherwise objectionable, the adjusting screw is turned to carry the pad inward into engagement with the face of the diaphragm, the screw being adjusted until the pressure of the pad upon the diaphragm is sufficient to modify or soften the tone to the desired extent, the pad yielding to enable this gradual modification.

The location of the adjusting screw permits of this sound modifying adjustment while a record is being played, so that the effects may be directly followed and adjustments made until the desired results are obtained. When the pad is adjusted outwardly and entirely free of the diaphragm,

the diaphragm is unrestrained and the attachment therefor has no effect on the same, but so long as the attachment remains on the sound box, it stands in position where it can be instantly adjusted at any time to modify the tone.

In the form of the invention illustrated in Fig. 3, the tone modifying pad is employed as before, but in this instance, the adjustment of the same is accomplished by means of a cam 24 pivoted on the supporting bridge piece or spider at 25 and arranged to bear on the outer end of the pad supporting pin. A spring 27 is shown provided for shifting the supporting pin outwardly and the outer end of the pin is shown as seating in notches or pockets 28 provided in the rim of the cam so as to give certain set adjustments. The cam is shown as provided with a finger lever 29 and suitable indications may be provided so that an operator may set the cam for "loud," "soft," "medium," etc.

In the form of the invention disclosed in Figs. 4 and 5, the modifying effect is obtained by means of a spring 30 of spiral conformation, supported at its center by a screw 31 which is adjustable similarly to the screw 17 for the purpose of shifting the spring toward and away from the diaphragm.

As this screw is turned to carry the spring element toward the diaphragm, the outer or larger convolution of the spring will be engaged with the diaphragm and then as the screw is turned farther, succeeding inner convolutions of the spring will be brought into contact with the face of the diaphragm. This results in the free vibrating area of the diaphragm being gradually reduced and on substantially concentric lines. Also, as the active area of the diaphragm is reduced in size, the pressure on the diaphragm is increased and this has a further modifying effect on the sound produced.

Preferably, the convolutions of the spiral spring which touch the diaphragm are provided with a rubber or other resilient covering, as indicated at 32.

This same progressive reduction in the active area of the diaphragm with gradual increase of exerted pressure may be accomplished in the first form of the invention illustrated. By making the resilient pad of conical or tapered construction, as indicated at 33, it will be engaged with the diaphragm first at its outer edge and will then, as it is compressed, gradually engage other inwardly located portions and thus gradually reduce the free area of the diaphragm.

Tone modifying effects similar to those described are attained in the form of the invention illustrated in Figs. 6 and 7 by the provision of a plurality of pads 34 mounted

on spring arms 35 pivoted on the pins 36, which latter are canted or inclined inwardly toward the center of the diaphragm so that as the spring arms swing inwardly to reduce the free area of the diaphragm, the pressure on the diaphragm is gradually increased. The several spring arms are shifted in unison, in the illustration, by means of an adjusting ring 37, rotatably mounted on the sound box and carrying pins 38 working in cam slots 39 in the spring arms.

It will be clear that upon the rotation of the adjusting ring 37, the pad carrying arms 35 will be swung inwardly or outwardly, as the case may be, and will in their inward swinging movement increase the tension of the pads on the diaphragm at the same time that the free area of the diaphragm is being gradually reduced. In the outer position of the arms, the pads will preferably stand free of the diaphragm, so that, as in the constructions previously described, the diaphragm may, when desired, be left free to vibrate in the usual way.

I find, with this invention, that not only is it possible to control the volume of sound, but also that the discordant sounds frequently produced can be eliminated and that the tone or musical quality can be greatly improved.

To avoid any possibility of breaking or injuring the diaphragm, I prefer to limit the extent to which the tone modifying element may be tensioned against the same. Thus, in Figs. 2 and 5, I have indicated how there may be provided a stop 40 on the adjusting screw which, as the screw is turned inwardly, will come into engagement with the bearing which supports the screw and will, therefore, positively limit the amount of tension which can be applied to the diaphragm. This stop also, it will be clear, limits the final reduction in size of the free area of the diaphragm.

What I claim is:

1. A tone modifier for phonographs comprising tone modifying means operable to engage successively smaller areas of the diaphragm of a sound box, and a control device for thus operating said tone modifying means to successively reduce the free vibrating area of the diaphragm.

2. A tone modifier for phonographs comprising a resilient tone modifying element and means for causing the same to successively reduce the free vibrating area of the diaphragm and for substantially simultaneously varying the pressure of the resilient element on the diaphragm.

3. A tone modifier for phonographs comprising a resilient tone modifying element and means for gradually causing the same to successively reduce the free vibrating area of the diaphragm and for gradually increas-

- ing the pressure of said element on the diaphragm as the free area of the diaphragm is restricted.
4. A tone modifier for phonographs comprising a resilient conical spring supported with the base of the same toward the diaphragm of a sound box, and means for bringing successively smaller convolutions of the same against the diaphragm independently of the stylus.
5. A tone modifier for phonographs comprising a resilient conical element and means for variably tensioning the same against the diaphragm of a sound box independently of the stylus to bring successively smaller portions of the same into engagement with the diaphragm to thereby gradually reduce the free vibrating area thereof.
6. A tone modifier for phonographs comprising a resilient hollow conical element supported with the base of the same toward the diaphragm of a sound box, means for variably tensioning the same against the diaphragm of a sound box independently of the stylus and means for forcing the same with increased pressure toward the sound box to thereby bring successive portions of the same into engagement with the diaphragm and to gradually increase the pressure of the same against the diaphragm. 30
7. The combination with the diaphragm of a phonograph, of means for gradually reducing the free area of said diaphragm and for substantially simultaneously applying increased pressure thereto. 35
8. A tone modifier for phonographs comprising a tone modifying element, means for variably tensioning the same against the diaphragm of a sound box and adjustable means for positively limiting the extent of such 40 adjustment.
9. A tone modifier for phonographs comprising a tone modifying element gradually engageable with successively smaller areas of the diaphragm of a sound box, means for 45 gradually adjusting said element into engagement with such successively smaller areas to thereby successively reduce the free vibrating area of the diaphragm, and means for positively limiting the extent of such 50 adjustment.

In witness whereof I have hereunto set my hand this 27th day of April, 1920.

EARL F. COPP.
